[57] CLAIM

The ornamental design for a display stand for flowers, as shown and described.

DESCRIPTION

FIG. 1 is a perspective view of a display stand for flowers showing my new design;

FIG. 2 is a front elevational view thereof; the side views being identical thereto;

FIG. 3 is a rear elevational view thereof;

FIG. 4 is a top plan view thereof;

FIG. 5 is a top plan view with the canopy removed for convenience of illustration; and

FIG. 6 is a bottom plan view of FIG. 1.

The showing of the electric cord broken away in FIGS. 1, 3 and 4-6 is for convenience of illustration.

FIG. 1

FIG. 2

FIG. 3

FIG. 4

FIG. 5

FIG. 6
